CLAIM

The ornamental design for a bicycle light, as shown and described.

DESCRIPTION

FIG. 1 is a front, left and bottom perspective view of a bicycle light design showing my new design.

FIG. 2 is a front, right and top perspective view of a bicycle light.

FIG. 3 is a rear, right and top perspective view of a bicycle light.

FIG. 4 is a front view of a bicycle light.

FIG. 5 is a rear view of a bicycle light.

FIG. 6 is a left side view of a bicycle light.

FIG. 7 is a right side view of a bicycle light.

FIG. 8 is a top view of a bicycle light; and,

FIG. 9 is a bottom view of a bicycle light.

The broken lines in the drawings depict portions of the bicycle light that form no part of the claimed design.
